UNITED STATES PATENT OFFICE.

FRANK B. CHAMBERLIN, OF COLUMBUS, OHIO.

FOUNTAIN-PEN FILLER.

Application filed March 6, 1928. Serial No. 259,548.

This invention relates to improvements in fountain pens or other analogous writing instruments, and has for its primary object the provision of a fountain pen wherein an improved mechanism is provided for filling the ink reservoir of the pen completely with the writing fluid.

In the majority of fountain pens now found in everyday use considerable difficulty is encountered in filling the ink magazine or reservoir with a sufficient quantity of the fluid to last for any appreciable length of time and it is necessary at relatively close intervals to refill the pen from time to time. 15 This is due to the fact that the ink reservoir or magazine is only partially filled with but a relatively small quantity of ink which soon becomes exhausted, and it is an object of the present invention to provide a more effective form of filling mechanism in connection with a fountain pen, by means of which the latter will be enabled to receive a much larger quantity of the writing fluid so that the necessity of frequent refills will be correspondingly reduced.

For further understanding of the invention reference is to be had to the description and the accompanying drawings wherein:

Figure 1 is a vertical sectional view taken 30 through a fountain pen constructed in accordance with the present invention.

Figure 2 is an enlarged vertical sectional view taken through the upper or bulb end of the fountain pen,

35 Figure 3 is a transverse sectional view taken through the line 3-3 of Figure 2,

Figure 4 is a vertical sectional view taken through a slightly modified form of bulb,

40 Figure 5 is a transverse sectional view on the line 5-5 of Figure 4.

Referring more particularly to the drawings the numeral 1 designates the barrel of a fountain pen constructed in accordance with the present invention. Generally, the barrel is of standard form, construction and size and may be formed from any suitable materials commonly employed in connection with writing instruments of this character. The barrel of the pen is provided with the usual pen point 2, against which is placed the usual feeder 3, which controls the flow of ink, or other writing fluid, from the ink reservoir or magazine 4 provided in the barrel 1 to the pen point 2.

45 The upper end of the barrel which is reduced in diameter as compared with the body

of the barrel, is provided with exterior threads 5 for the reception of a removable bulb protecting cap 6. This cap is of tapered form to receive the removable shell 7 when 60 the pen is in use. It will be understood that the shell is adapted to be applied to protect the pen point when the fountain pen is being carried or is out of use as is customary.

Situated in the upper end of the barrel is 65 a plug 8 which closes the upper end of the reservoir 4. Carried by the plug and extending axially throughout the length of the reservoir is a major air expelling tube 9. The upper end of this tube communicates with the 70 interior of a collapsible bulb 10, which is formed from rubber or other equivalent material. The lower end of the bulb is cemented or otherwise fastened to a boss projecting from the upper portion of the plug 8. The 75 lower end of the tube 9 terminates in the ink passageway 11 which is provided between the pen point 2 and the feeder 3. Also carried by the plug 8 is a short or minor tube 12, which is formed from a collapsible material such 80 as the material employed in the bulb 10. The lower end of the short tube 12 terminates in communication with the upper portion of the reservoir 4, while the upper end of said tube terminates adjacent to the top of the bulb 10. 85

In operation, when it is desired to refill the reservoir of the pen with ink, the cap 6 is first removed so that the bulb 10 will be rendered accessible. The pen point is then submerged in a body of ink, and the bulb 10 is 90 compressed so as to expel the air from the interior of said bulb by way of the major tube 9 and the passageway 11. Then when the bulb is released the exterior air pressure on the body of ink forces the ink upwardly into 95 the reservoir 4 to an extent governed by the expulsion of the air when the bulb was first collapsed. This single operation, however, only partially fills the reservoir or magazine, and in order that further or a complete filling 100 of the reservoir may be obtained, the bulb 12 is again collapsed exhausting a still further quantity of air from the reservoir or the bulb 10, permitting of an additional ink flow into said reservoir. It will be observed that 105 when the bulb is compressed the pressure applied by the operator also acts to compress or close the short tube 12 so that the displaced air will be forced through the major tube 9 and not through the minor tube 12. It is for this 110 reason that the tube 12 is formed from a compressible material, and in this connection I

may state that experience has demonstrated that the collapsible tube 12 is very effective in preventing return flow of air to the barrel during the filling operation. Beside being extremely simple in construction the tube 12 functions very positively and is superior to check valves and other similar devices which I have employed. It can be seen that the contraction and expansion of the bulb extrudes air from the barrel and permits of its expulsion through the tube 9 so that the barrel and in fact even the bulb may be completely filled with ink. After this the cap 6 is restored to its operative position and the pen is then ready for use.

In the modified form of the invention disclosed in Figures 4 and 5 the bulb 10^a is formed to include an exterior groove 13, in which the tube 12^a is positioned. By locating the tube 12^a to the exterior of the bulb 10^a the operator is enabled to apply pressure at the most effective points to secure the desired operation. This can be accomplished skillfully in the modified form of the invention since the tube 12^a is exposed to view and may be readily compressed by the operator. I have disclosed what I consider to be the preferred forms in the present invention but nevertheless it will be understood that changes or variations may be made in the construction of the pen from that herein specifically shown and described, without departing from the scope and operation of the invention as the latter has been defined in the subjoined claims.

What is claimed is:

1. In a fountain pen, a barrel including an internal ink reservoir, a tube extending through said reservoir from one end thereof to the other, a bulb of compressible material secured to one end of said barrel, the interior of said bulb being in communication with one end of said tube, a secondary tube in communication with said reservoir and with the upper end of the interior of said bulb, said secondary tube being adapted to be closed when said bulb is compressed.
2. In a fountain pen, a barrel including an ink reservoir, a bulb carried at one end of said reservoir, a tube leading from the interior of said reservoir into the said bulb and operable to permit of the flow of air from said reservoir into said bulb, said tube being formed from a collapsible material to prevent the flow of air from the bulb into the reservoir when said bulb is being compressed,

and an air exhaust tube leading from the interior of said bulb to the exterior of the pen.

3. In a fountain pen, a barrel including an internal ink reservoir, and a closure at one end of said barrel, a collapsible bulb carried by said closure, a tube extending axially through said reservoir, one end of said tube being in communication with the interior of said bulb and the other end of said tube leading to the exterior of the pen, whereby upon the collapse of the bulb the displaced air is discharged from the pen by way of said tube, and a compressible tube communicating with said reservoir and with the upper and inner end of said bulb, the said collapsible tube being adaptable upon compression of said bulb to close in order to prevent return flow of air from said bulb into said reservoir, the expansion of said bulb permitting of the flow of air from said reservoir into said bulb by way of the collapsible tube.

4. In a fountain pen, a barrel including an internal ink reservoir, and a closure at one end of said barrel, a collapsible bulb carried by said closure, a tube extending axially through said reservoir, one end of said tube being in communication with the interior of said bulb and the other end of said tube leading to the exterior of the pen, whereby upon the collapse of the bulb the displaced air is discharged from the pen by way of said tube, and a compressible tube communicating with said reservoir and with the upper and inner end of said bulb, the said collapsible tube being adaptable upon compression of said bulb to close in order to prevent return flow of air from said bulb into said reservoir, the expansion of said bulb permitting of the flow of air from said reservoir into said bulb by way of the collapsible tube.

5. In a fountain pen, a barrel including an ink reservoir, a closure for the upper end of said reservoir, a bulb of collapsible material carried by said closure, an air exhaust tube carried by said closure and communicating at one end with the interior of said bulb, the other end of said tube leading to the exterior of said pen, said bulb being provided with a vertically extending groove, and a tube of collapsible material positioned on said groove, said collapsible tube communicating at one end with the upper position of said reservoir and at its opposite end with the upper and inner portion of said bulb.

In testimony whereof I affix my signature.

FRANK B. CHAMBERLIN.
